ATTYS.

UNITED STATES PATENT OFFICE.

GEORGE WASHINGTON ABRAHAM, OF WESTON, ONTARIO, CANADA.

FIREARM.

1,190,070.

Specification of Letters Patent.

Patented July 4, 1916.

Application filed October 18, 1915. Serial No. 56,547.

To all whom it may concern:

Be it known that I, GEORGE WASHINGTON ABRAHAM, of the town of Weston, in the county of York, in the Province of Ontario, 5 Canada, have invented certain new and useful Improvements in Firearms, of which the following is the specification.

My invention relates to improvements in fire arms (covered by my application Ser. 10 No. 29,810, dated May 22nd, 1915) and the object of the present invention is to devise means for insuring that each succeeding cartridge is fired by the back fire of the preceding cartridge and thus prevent any of 15 the cartridges missing and it consists essentially of a barrel block and a co-acting breech block having recesses into which the bases of the cartridge fit, a continuous groove or channel extending diametrically 20 through each recess, and a deflector extending from the base of the recess across the groove and into the ignition chamber of the cartridge which would be left free or clear of any primer, the parts being arranged and 25 constructed as hereinafter more particularly explained.

Figure 1 is a plan section of the weapon showing my improvement. Fig. 2 is an elevation partially broken away and in a section to exhibit the parts involved in my invention. Fig. 3 is an enlarged plan section 30 of a portion of the weapon showing the deflector. Fig. 4 is an enlarged section at right angles to that shown in Fig. 3. Fig. 35 5 is a perspective broken away detail of a portion of the breech block showing the recess, the groove extending diametrically through the recess and the deflector removed from its recess.

40 In the drawings, like letters of reference indicate corresponding parts in each figure.

1 indicates the barrel block provided with a series of barrel bore portions 2.

3 indicates the hammer.

45 4 indicates a plate provided with barrel bore portions 5 arranged in the plate so as to be located opposite each of the barrel bore portions 2 of the barrel block 1.

6 indicates the breech block comprising 50 the body portion 7 forming the back of the breech block and having recesses 8 to receive the large ends of the cartridges and an end wall 9 forming a closure for one end of the channel-way.

55 10 indicates a groove or channel-way

formed in the inner face of the breech block 6.

11 indicates a percussion cap chamber formed partially in the barrel block 1 and breech block 6 and partially in the body of 60 the pistol, the outer end of the percussion cap chamber being open and formed in the usual way to allow of the striking of the hammer against the cap and into which the left hand end of the grooved portion 10 65 is connected.

12 indicates the percussion cap which fits into the percussion cap chamber in the usual way.

13 indicates a cartridge with back portion 70 14 fitting into the recess 8 and having the free ignition chamber 15.

16 indicates a deflecting member having the cylindrical portion 17 extending into a recess in the breech block 6 and having a 75 substantially flat V-shaped reduced portion 18 entering into the ignition chamber 15 of the cartridge.

As an alternative construction the projecting portion 18 may be made integral with 80 the breech block 6.

Having described the principal parts involved in my invention I will briefly describe the operation of the same.

When it is desired to fire the weapon, the 85 trigger 3 is pulled so that the hammer ignites the cap 12, the flash of which passes up the grooved portion 10, strikes the extending portion 18 of the deflecting member igniting the first cartridge. The back fire of the 90 first cartridge will be divided by the substantially V-shaped extending portion 18, part going back toward the hammer and being lost, while the rest travels along the channel-way 10 to the next cartridge firing 95 it and so on, each preceding cartridge firing the next succeeding one. Hence it will be seen that I have devised very simple means whereby by the ignition of a single percussion cap by any suitable firing means each 100 succeeding cartridge is fired by the back fire of the preceding cartridge.

What I claim as my invention is:

1. In a weapon of the class described, the combination with the barrel block, of a 105 breech block having recesses to receive the bases of cartridges provided with free ignition chambers and the usual firing perforation, means for creating an initial ignition flash to fire one cartridge through its igni- 110

- tion chamber, and means for directing the back flash of each preceding fired cartridge into the ignition chamber of the next succeeding cartridge and through the firing 5 perforation thereof.
2. In a weapon of the class described, the combination with the barrel block, of a breech block having recesses to receive the bases of cartridges provided with free ignition chambers and the usual firing perforation, and a groove communicating with each cartridge ignition chamber, means for creating an initial flash at one end of the groove for firing the first cartridge, and 10 means for directing the back flash of each preceding cartridge into the ignition chamber of the next succeeding cartridge and through the firing perforation thereof.
3. In a weapon of the class described, the combination with the barrel block, of a breech block having recesses to receive the bases of cartridges provided with free ignition chambers and the usual firing perforation, and a groove intercommunicating be- 15 tween the ignition chambers of all the cartridges, and deflectors extending across the groove into and diametrically across the ignition chamber of each cartridge and firing perforation 40 thereof.
4. In a weapon of the class described, the combination with the barrel block, of a breech block having recesses to receive the bases of cartridges provided with free ignition chambers and the usual firing perforation, and a groove intercommunicating be- 20 tween the ignition chambers of all the cartridges, and deflectors extending across the groove into and diametrically across the ignition chamber of each cartridge and firing perforation 45 thereof.
5. In a weapon of the class described, a breech block in which the bases of a plurality of cartridges are adapted to be located, said block having a firing groove, and a de- 45 flector interposed in the length of the firing groove opposite the base of each cartridge adapted to divide the back flash from each cartridge.
6. In a weapon of the class described, a breech block having a firing groove, a plurality of free ignition chamber cartridges whose bases are adapted to be located in said block, a deflector interposed in the length of the firing groove opposite the base of each cartridge and extending into the ignition chamber thereof adapted to divide the back 50 flash from each cartridge.
7. In a weapon of the class described, a breech block in which the bases of a plurality of cartridges are adapted to be located, said block having a firing groove and a rounded knife-edged deflector interposed in the length of the firing groove opposite the base of each cartridge adapted to divide the back flash from each cartridge. 55

GEORGE WASHINGTON ABRAHAM.
